UNITED STATES PATENT OFFICE.

JOHN R. HAMILTON, OF YONKERS, NEW YORK, ASSIGNOR TO AUTOMATIC SPRINKLER COMPANY OF AMERICA, OF NEW YORK, N. Y., A CORPORATION OF NEW YORK.

DESIGN FOR A RETAINER-LEVER FOR A SPRINKLER-HEAD OR SIMILAR ARTICLE.

55,038.

Specification for Design.

Patented May 4, 1920.

Application filed July 22, 1919. Serial No. 312,582. Term of patent 14 years.

To all whom it may concern:

Be it known that I, JOHN R. HAMILTON, a citizen of the United States, residing in Yonkers, county of Westchester, State of New York, have invented a new, original, and ornamental Design for Retainer-Levers for Sprinkler-Heads, &c., of which the following is a specification, reference being had to the accompanying drawing, which forms part of the same, and in which—

Figure 1 is an elevation showing the co-

operating retainer levers for a sprinkler head embodying my new design; and

Fig. 2 is a perspective view thereof showing them at a somewhat different angle.

What I claim is:

The ornamental design for a retainer lever for a sprinkler head or similar article, substantially as shown.

July 19th, 1919.

JOHN R. HAMILTON.
